To all whom it may concern:

Be it known that I, GUSTAV KOLB, a citizen of the United States, and a resident of New York city, county and State of New York, 5 have invented a new and original Design for a Mirror-Back or Similar Article, of which the following is a specification, reference being had to the accompanying drawings, in which—

Figure 1 represents a view of a mirror-back 10 embodying the design, and Fig. 2 is a cross-section on line 2 2, Fig. 1.

The leading feature of the design consists of a cupid *a*, seated within clouds *b* above a scroll *c* and grasping a flowering twig *d* with 15 one of his uplifted hands.

The design is applied to mirror-backs, brushes, manicure sets, bonbon-dishes, compots, ink-tops, puff-boxes, and jewel-boxes.

What I claim is—
